INVENTOR.

BY *Richard B. Oliver*

ATTORNEY.

UNITED STATES PATENT OFFICE.

HENRY MEYER, OF ANDERSON, INDIANA.

PERPETUAL CALENDAR.

Application filed July 16, 1927. Serial No. 206,281.

This invention relates to indicators and more particularly to an indicator for use in hospitals, sick rooms and the like for indicating the time at which certain medicines are to be taken by a patient.

One of the primary objects of the invention is to provide a medicinal indicator including a base plate having a clock face stamped or affixed thereon with a plurality of different colored hands, the hands being adapted to be freely set to different points of time for indicating the time and intervals at which different medicines are to be taken by a particular person, each of the hands being of a distinctive color and each representing a particular kind of medicine, whereby the different medicines may be accurately administered to a patient at the desired time.

20 A further object of the invention is to provide a medicinal indicator comprising a base plate having means thereon for indicating the time at which said medicines are to be taken and a thermometer and calendar thereon so as to increase the service of the indicator.

25 A further object of the invention is the provision of novel means arranged at one side of the clock face on the face plate for indicating the day of the month, said means including a pointer movable in a vertical slot, the face plate on opposite sides of the slot being marked with the days of the month, so that the pointer can be moved up or down the slot for alinement with any one of the numerals indicating the day, the pointer being rotatable so as to permit the same to be moved from one side of the slot to the other.

30 A further object of the invention is the provision of dials carried by the upper end of the face plate for indicating the day of the week, the month, and the number of days in the month.

35 A still further object of the invention is to provide an improved medicinal indicator of the above character, which will be durable and efficient in use, one that will be simple and easy to manufacture, and one which can be placed upon the market at a very small cost.

With these and other objects in view, the invention consists in the novel construction, arrangement and formation of parts, as will be hereinafter more fully described, claimed, and illustrated in the accompanying drawings, in which drawing:

Figure 1 is a front elevation of the improved device,

Figure 2 is a side elevation of the improved device,

Figure 3 is a vertical detail section taken on the line 3—3 of Figure 1 looking in the direction of the arrows, illustrating the method of mounting one of the rotatable indicating disks upon the face plate,

Figure 4 is a detail horizontal section taken on the line 4—4 of Figure 1 looking in the direction of the arrows, illustrating the means of mounting the indicating hands upon the medicinal indicator, and

Figure 5 is a detail horizontal section taken on the line 5—5 of Figure 1 looking in the direction of the arrows, showing the method of mounting the indicating pointer for the calendar on the base plate.

Referring to the drawings in detail, where-in similar reference characters designate corresponding parts throughout the several views, the letter A generally indicates the improved device, which comprises a face plate 10 which can be formed of any preferred material, such as light sheet metal, celluloid, cardboard or the like. The central portion of the face plate has marked or stamped thereon in any preferred way a clock face 11 for indicating the hours of the day and the axial center of the clock face receives a rivet 12 which rotatably supports three indicating hands which are indicated by the reference characters 13, 14, and 15 respectively. These hands are of a different color, so that each one can be readily distinguished from the other and the hand 13 is preferably colored red, the hand 14 white, and the hand 15 blue.

The clock face 11, and the hands 13, 14 and 15, form the medicinal indicator, per se, and the same is used as follows: It is often necessary in sick rooms that a patient be given a number of different kinds of medicine at

different intervals of time. To prevent confusion, each hand represents a particular kind of medicine and the hands are set on the different hours, at which the different kinds of medicines are to be administered. As the medicine is given the patient, the hand is set up to the desired new interval of time. If preferred, in order to reduce all possibility of confusion the different bottles of medicine can be labeled "Red", "White" and "Blue", respectively so as to indicate which hand the medicine represents.

Below the clock face a line 16 is drawn and the space below the line is left blank for the reception of suitable advertising matter or the like so that the complete device can be placed on the market as an advertising novelty.

Mounted upon the base plate 10 preferably to the left of the clock face 11, is arranged any preferred type of thermometer 17 and the face plate 10 itself can be graduated, as at 18, along the stem of the thermometer.

To the right of the clock face, the face plate 10 is provided with means 19 for indicating the days of the month and this means comprises a pointer 20 which is slidably mounted within a vertical slot 21 formed directly in the face plate. The face plate on opposite sides of the slot 21 is graduated as at 22 and the days of the months are stamped, printed or otherwise affixed to the face plate adjacent to said graduations. The pointer 20 is mounted in a novel manner so that the same can be swung to either side of the slot for indicating the particular day of the month and this means includes a shank 24 having a flat head 25 at its rear end for engaging the face plate. The forward end of the shank is provided with a manipulating handle 26 and rotatably mounted upon the shank between the face plate 10 and the manipulating handle 26 is the pointer 20. It is obvious that by grasping the handle 26 the pointer can be moved up or down in the slot to the desired position, and the pointer can be swung either to the right or the left to indicate the desired day of the month.

Above the clock face 11, the thermometer and the day of the month indicator 19 I provide the face plate with three rotatable disks 27, 28, and 29. These disks are disposed in rear of the face plate and are connected therewith by the use of suitable rivets or the like 30. The disk 27 has printed or otherwise formed thereon the month of the year, while the disk 28 has printed or otherwise secured thereon the days of the week, and the disk 29 has printed or otherwise secured thereon the number of days in a particular month and the face plate is provided with slots 31 which forms sight openings so that the desired indicia on the disks will be brought into registration with the sight openings and thus be brought into view.

From the foregoing description, it can be seen that I have provided a novel device which is particularly adapted for use in sick rooms.

The device can be hung up on a wall or placed in an upright position on a table or the like and in order that the same may be placed upon the table in an upright position I provide a foot 32 which is secured to the rear face of the face plate and which terminates in substantially the same plane with the lower edge of the face plate, so as to form a support therefor.

Changes in details may be made without departing from the spirit or scope of this invention, but:

What I claim as new is:

A device of the class described, a face plate, disks rotatably carried by the face plate and a mark thereon for the days of the week, the month of the year, and the number of days in a particular month respectively, the face plate having sight openings therein through which portions of the indicia on the disks can be seen, the face plate being further provided with a vertical slot, numerals on opposite sides of the slot indicating the days of the month, and an indicating pointer for the numbers indicating the days of the month rotatably and slidably mounted in the slot.

In testimony whereof I affix my signature.

HENRY MEYER.
